IRONING BOARD

Henrietta Adamec, New York, N. Y.

Application October 17, 1946, Serial No. 703,921

2 Claims. (Cl. 38—107)

1

This invention relates broadly to all ironing boards and ironing tables whereupon a sad iron is used, and more particularly to ironing boards of the types employed by the housewife in the home.

One object of my invention is to provide an ironing board having an air-insulated sad iron holder (I having found by experiment that an air space was a better insulator than other materials used), and the sad iron holder having its upper surface flush with the ironing surface of the pad-and-cloth element so that the iron requires no lifting during its travel to and from the holder; and said holder being located at one end of the board so that it may be reached without departing from a continuation of the straight line ironing motion and direction. The addition of the holder also eliminates necessity of tilting a sad iron in rest, in which position its heated bottom would be exposed to easily burn a person or the iron easily fall. The addition of the holder does not decrease the ironing space in view that the butt area of the board is generally reserved for resting the sad iron.

Another object is to provide an ironing board having the iron holder located within the perimeter of an ordinary shaped ironing board so that it does not extend to where it may easily be contacted and burn a person's hand or arm or within reach of children's hands on the edge of the board; and which iron holder is permanently fastened to the board, thereby requiring no extra handling or adjusting to put away after use and thereby avoiding possibility of burning one's hand when the holder is hot, and eliminates the possibility of the hot holder and its contained sad iron from accidentally falling off the board on to the floor or on children.

Another object is to provide an ironing board having the ironing cloth to not extend over the butt end of the board, and thus prevents soiling and wearing of the ironing cloth when the ironing board is folded up and standing on its butt end upon the floor.

Another object is to provide an ironing board having the iron holder to not rest on the ironing cloth, nor contact therewith, thereby preventing the iron holder when hot, from wearing out the cloth, and thus gives the cloth a longer life, avoiding frequent cloth replacement.

Another object is to provide an ironing board having a cord guiding element to prevent the said iron cord from dangling and rubbing on the work being ironed and causing the work to become soiled, or catching on the edge of the work and wrinkling it.

2

A further object of my invention is to provide an ironing board comprising the combination of all the above said objects, and which is engineered to assure better utility than heretofore types, having a more pleasing appearance and which is designed to allow more efficient manufacturing methods for producing such type of ironing board.

These and other objects may be discovered upon study of this specification and the accompanying drawings wherein:

Figure 1 is a perspective assembly view of the ironing board invention showing a sad iron in operative position thereupon.

Figure 2 is a fragmentary plan view of the assembly.

Figure 3 is an enlarged cross-sectional view approximately through 3—3 of Figure 2.

Figure 4 is an enlarged cross-sectional view approximately through 4—4 of Figure 2.

Figure 5 is a perspective view of the ironing board showing the ironing cloth partially lifted up and a portion of the ironing pad broken away to show the ironing cloth clamping mechanism here shown in released position.

Figure 6 is an enlarged cross-sectional view through 6—6 of Figure 5, showing the clamp in clamped position.

Figure 7 is a bottom assembly view.

Figure 8 is a bottom view of the ironing cloth in a flat position.

Figure 9 is a perspective view of one of the parts of the ironing cloth clamping mechanism.

Figure 10 is a plan view showing variations of the present invention as applied to a metal ironing board.

Figure 11 is a cross-sectional view through 11—11 of Figure 10.

Figure 12 is a plan view of a wooden ironing board showing further variations of the present invention.

Figure 13 is a cross-sectional view through 13—13 of Figure 12.

Figure 14 is an enlarged cross-sectional view through 14—14 of Figure 12.

Figure 15 is a fragmentary plan view of a wooden ironing board showing a further variation of the present invention.

Figure 16 is a bottom assembly view of a further variation of the present invention.

Figure 17 is a cross-sectional view through 17—17 of Figure 16.

Figure 18 is a cross-sectional view through a similar portion as is Figure 3, showing a further variation of the cloth clamping mechanism.

Figure 19 is a cross-sectional view through a

similar portion as is Figure 3, showing a further variation of the cloth clamping mechanism.

Referring to the drawings in detail, and particularly to Figures 1 to 9, inclusive, thereof, wherein the present invention is shown in its most preferred form, the ironing board embodying the present invention comprises an ordinary ironing board 20 with or without legs structure, and certain other elements specified hereinafter combined therewith.

At the butt end 21 of the board and on the upper surface 22 thereof, an iron holder 23 is fastened thereto by screws or other securing means 24 which are flush with the upper surface of the holder, said holder being of metal or other suitable material. The iron holder comprises principally a broad plate 25 upon whose upper surface 26 a sad iron 8 may be supported, and the holder is formed with downward extending flange 27 to contain an insulating air space 28 between the plate and the board, and the holder rests upon its flanges against the board. Upward extending flanges 29 are formed on all sides of the plate except on the side adjacent the ironing portion of the board, and are for the purpose of arresting the sad iron from sliding off the holder and falling on the floor. The said side not having the upward flange has a gently curving edge 30 leading into a said downward flange.

Also located on the butt portion of the ironing board is a sad iron cord guiding element 31. The cord guiding element as illustrated in the drawings, Figures 1 to 11 inclusive, is formed from a round metal rod of a diameter slightly less than the height of the air space between the holder and board, but may be made from any other suitable material which can provide its fundamental features hereinafter specified. The cord guiding element comprises a pivoting arm 32 the pivoting end of which has a flat portion 33 and a hole 34 therethrough and at the other end a formed loop 35, said loop having a restricted opening 36 through one point of its rim to the outside, the said opening being of a width slightly narrower than the thickness of a sad iron cord C so to allow insertion of the cord therethrough upon slight force but to not allow the cord to freely fall out therethrough from the loop. The cord guiding element is located to pivot at its hole about one of the holder securing screws 24 at a point between the holder and the board. On the side of the holder which faces the rear of the board 37 an opening 38 is provided in the downward flange through which the cord guiding element extends. In operative position the cord guiding loop lays beyond the ironing board rear edge 39 as shown in Figs. 1, 2 and 10 of the drawing, and when not operative it may be stored away by being pivoted to come within the perimeter of the ironing board until the loop rests within the space between the holder and the board, as shown in phantom in Figure 2. An extension on the guide element beyond the loop serves to form a stop 40 which limits the outward pivotal travel of the guide element by butting against the inner wall 41 of the depending flange 27. A downward depression in the holder plate forms stop 42 which maintains the guide element in operative position preventing its pivotal return upon ordinary ironing stresses. Another similar stop 43 in the holder plate maintains the guide element in stored position preventing its travel to beyond the board perimeter where it may easily get damaged. The inward pivotal travel is limited by opening 38 in

the holder flange being short of fully admitting the guide element causing thereby the guide element at its point 44 to butt against the outer wall 45 of the depending flange 27 as shown in phantom of Figure 2. A portion 46 of the guide element is formed to serve as an accessible handle which may be grasped by the operator to move the guide element from a stored position to an operative one.

- 10 On the generally tapered end 47 of the board and extending to adjacent the iron holder is laid a pad 48 of felt or other suitable material, and on top of the pad, a detachable pad cover 49 made of fabric, plastic or other suitable material, which extends around the adjacent edges 50, 51 and 52 of the board. The pad cover is of a generally rectangular shape wherein one end is generally tapered and rounded as illustrated in Figure 8 and as is well known in ironing board pad cover art. An enclosed slot 53, formed by folding over the edge and sewing it at 54, is made on all sides of the pad cover except on the butt edge 55, said slot having an opening 56 at its two ends. Within the slot, and extending out of its openings and across the space between the openings is an elastic cord band 57. A rivet 58 at each end of the slot re-enforces the sewing from unravelling when the elastic cord stresses the pad cover.
- 15 30 On the butt end of the ironing surface of the board and adjacent the iron holder a clamp mechanism 59 is provided for the purpose of securing the butt edge of the pad cover. One of the parts comprising the clamp mechanism is a clamp 60 extending the width of the board and secured along its immovable edge 61 by a plurality of nails or other means 62 to the upper surface of the board and the active edge thereof forming a jaw 63 facing the iron holder and being active against the upper surface of the board, and the said clamp being of spring metal material and when free being urged open. The active edge may or may not have teeth as shown in the drawing for the purpose of gripping the pad cover. Through the said clamp active edge a plurality of holes 64 are provided, and corresponding holes 65 through the ironing board, through which depend linkages 66 having low heads 67 at their upper ends bearing against the upper surface of the clamp. The said linkages at their lower end are provided with heads 68 between which and the lower surface 69 of the ironing board, is an operative wedge 70. The said wedge comprises a plate 71 having a plurality of double tongues 72 inclined respective to the lower surface of the ironing board, between which double tongues is a slot 73 wherethrough pass the stems of the depending linkages, whose lower heads bear on the underside of the tongues.
- 20 40 50 60 The said wedge element is mounted on the lower side of the ironing board by a nail or screw 74 which passes through slot 75 of the wedge, sufficient clearance being provided between the slot sides and nail, and between the nail head and bottom of the board to permit sliding of the wedge, from a position as shown by solid lines in Figure 6 of the drawings to a position as shown by phantom lines in the same figure. The travel of the wedge element is limited to the length of slot 75 active on fixed nail 74. The wedge element is bent at one end to form a push-pull handle 76 to permit grasping thereof, on which operative directions may be printed (as shown in the drawings). Holes 77 are provided at the end 75 of slot 73 for purpose of assembling the clamp

element, the lower head 68 of the linkage passing therethrough.

The operation of the clamp element is as follows: Pulling or pushing the wedge element handle transversely to the board causes the inclined double tongues to travel past the depending linkages from their uppermost to lowermost portion, or visa versa. When the lowermost portions are active against the linkages they force the linkages downward thereby causing the latter to force the clamp jaw to lock down against the upper side of the board. When the uppermost portions of the double tongues are active against the linkages they release their force therefrom, thereby permitting the clamp jaw to open upward.

A further feature of the double tongues is that the inclined rising portion thereof varies at each station of double tongues in a manner so that they are active consecutively and not simultaneously with tongues of another station, which is accomplished by the distance between the rise at one station to the rise at another station being not the same as the distance between the linkages of those stations, the purpose for this being to divide into small parts the effort required by the operator to accomplish a clamp movement operation.

To place the replaceable pad cover on the ironing board the following procedure is used:

The pad cover is inserted, butt end first and top side up, over the tapered end of the board and the elastic cord of the butt side, below the board. The cover is pulled on until its butt edge meets the iron holder. The clamp operative handle is pulled outward, the clamp thus opening. The butt edge of the pad cover is folded under and slipped into the mouth of the clamp. The clamp is then closed down on the pad cover. Those edges of the pad cover with the elastic cord sewn therein are now slipped over the edge of the ironing board onto the bottom side. To remove the cover, the operation is performed in reverse procedure.

My invention is not limited to the construction hereinabove described, but may include such variations as will come within the scope of my claims. Certain of such variations are shown in Figures 10 to 19, inclusive, of the drawings wherein numerals suffixed by letters refer to like parts designated by similar numerals hereinabove.

One variation of the present invention as applied to a metal ironing board is shown in Figures 10 and 11 wherein the iron holder 78 is formed from a continuation of the ironing portion 79 of the ironing board, and the holder portion being bent upward so to be flush with the ironing surface. Insulation of the iron holder from the remainder of the ironing board is accomplished by slots 80 cut through all around. The edge areas 81 of the butt of the board are bent further upward to a level higher than the iron holder, thereby forming means for arresting the flat iron from sliding off the holder. The cord guide element 31A is operative within the horizontal plane space between the said edge areas and the iron holder. The cloth clamping device shown in Figures 10 and 11 comprises a flat bar clamp 82 having a plurality of grooves 83 on one edge, the said clamp being removably clipped under the heads of bolts 84 in a manner so that the bolts pass through the grooves, said bolts continuing through the ironing board and being actuated therebelow by wing nuts 85.

In Figures 12 and 13 is shown a variation of the cord guiding element comprising an aperture

86 through a wooden ironing board 20B having a restricted opening 87 on the rear edge 39B of the ironing board butt portion 21B, all edges of the aperture being rounded to prevent wearing out the sad iron cord. The iron holder 23B shown in Figures 12 and 13 serves also as the ironing pad cover butt edge clamp, thus requiring no extra clamp device. In the present variation the holder has a plurality of lugs 88 on its rear-butt edge, holes 89 through said lugs, and securing screws 24B through said holes and screwed hard down into the ironing board. The depending side of the holder 27B, which is adjacent the ironing area comprises a clamping jaw 90 active against the upper surface of said ironing board. The edge may or may not be serrated for improved clamping grip. The active end of the holder, containing the jaw is held to the board by bolts 91 in a manner as specified above. By releasing wing nuts 92 the clamping jaw opens upward, due to lugs 88 being bent slightly upward (as shown in Figure 13) and screws 24B being screwed down hard as said, thereby causing the freed active side of the holder to rise sufficiently to allow the toward-butt edge of the ironing pad cover to be inserted or removed from between the jaw and board. As a further variation, instead of the slight upward bend of the lugs, a spring may be used between the active part of the holder and the board. Cooling vents 93 in the holder and holes 94 in the board may or may not be used.

In Figure 15 is shown a variation of the cord guiding element shown in Figure 12, in the present figure being shown opening onto the butt edge 35 of the ironing board and wherein consideration is made for an easier manufacture of the aperture 87C, the opening thereto being restricted by an ordinary flat spring 95 mounted at 96 and bridging the opening.

In Figures 16 and 17 is shown a variation which permits use of a pad cover 49A of conventional design having gathering means on all edges, thereby requiring no clamp device. The board 20D is in two parts 97 and 98 separated by space 99, the two parts being fastened rigidly together by bracket 100, and space 101 under the butt end of the board 97 being provided.

Also in Figure 17 is a variation of the insulation 28A between the holder 23D and the board 98, here being shown of asbestos 28A.

Another variation of the clamp is shown in Figure 18 wherein a plurality of holes 102 are provided in the board 20E to contain clamping mechanism 103 wherein pivots 104 and 105 are fixed to the board and linkage 106 is rigid to the holder 23E. By prying holder upward with a fingernail in groove 107 the holder pivots at 104 thereby transmitting movement through link 108 and causing clamp 109 to pivot at 105 and opening clamp jaw 110. A spring 111 urges the clamp to normally stay closed and the holder down against the board, by bearing against the pin at pivot 112.

In Figure 19 a variation of the clamp device is shown wherein linkage 66A is firmly fastened to clamp 113, in the present figure by riveting, thereby eliminating requirement of a spring to open up the clamp, in view that the linkages are forced upward by a certain said travel of the wedge element 70A due to said linkages being vertically locked by their necks 114 between forked double tongues 72A of the wedge element. As a further variation in Figure 19 the ironing pad 48A extends only to adjacent the clamp, thereby permitting

space for a stronger construction of the clamp, in the present figure shown channeled.

What I claim as my invention and desire to secure by Letters Patent is:

1. In combination with an ironing board and on the butt end thereof, a metal tray, a padded element covering the generally tapered end of said ironing board and extending longitudinally over a major portion of said ironing board to adjacent said tray, said tray having an upwardly extending wall on all sides of its upper surface except on the side adjacent said padded element, and upper surface of said padded element being substantially flush with upper surface of said tray, said tray having a downwardly extending flange resting on the board for elevating the upper surface of said tray, fastening elements for securing the tray to the ironing board, said tray having an opening at one side, a cord holder adjustable in and out of said tray opening and retained for adjustment by one of said fastening elements for the tray.

2. In combination, an ironing board having a butt end and a tapered end, a metal tray adapted to be secured to the butt end of the board, a padded element extending over the tapered end of the ironing board, said tray having an upper surface and upwardly extending flanges on all

10 sides of said surface except on the side adjacent to the padded element, said tray having a downwardly extending flange resting on the board for elevating its upper surface to a location substantially flush with the upper surface of the padded element, fastening screws adjustable through the tray for securing the tray to the ironing board, said tray having an opening at one side of the same, a cord holder pivotally connected to the tray and board by one of said fastening screws and adjustable in and out of said opening, said tray having depression stops for limiting the inward and outward movement of said cord holder.
